UNITED STATES PATENT OFFICE.

WILLIAM H. HARRISON, OF PHILADELPHIA, PENNSYLVANIA; NELLIE HARRISON EXECUTRIX OF SAID WILLIAM H. HARRISON, DECEASED.

SHUTTLE.

Application filed January 15, 1927. Serial No. 161,276.

My invention relates to shuttles used in weaving.

In the use of shuttles in weaving, particularly with rayon, it has been found desirable, owing to the action of the rayon as it comes off the bobbin or tube in flying about, unwinding too rapidly and becoming entangled or disarranged, whereby the thread may be broken or its feeding through the shuttle interrupted or stopped, to cover the bottom and the sides, partially, of the recess in which the bobbin is carried with a fur or fur-like material or pile fabric or other suitable material; as the thread unwinds from the bobbin it contacts with this fur-like lining which serves to prevent said actions and to feed the thread through the shuttle in a normal manner. Heretofore, in practice, this material forming the lining has been secured to the bottom and sides of said recess by first applying glue thereto, applying glue to the piece of hide or other material which has been cut to proper dimensions and then fitting and pressing the latter within the recess against the glued surface thereof. Among the many disadvantages in this manner of lining the shuttle are the extreme care required in applying the glue neatly within the recess so that it will not extend without the lining after the same is in position, the like care required in applying the glue to the lining to prevent the fur side of the hide from becoming smeared with the glue, the difficulty in properly positioning the lining within the recess without smearing its sides, the loss of use of the shuttle while the lining is being placed therein and the glue is drying, and the expense of labor. Additionally, these linings wear out from use and their replacement with other linings is required. This replacement is attended with further disadvantages in the removal of the worn out lining, in the scraping off of the old glue from the bottom and sides of the recess and in the loss of use of the shuttle during the lining replacement.

Among the objects of my invention is to provide a shuttle by which all of the disadvantages above stated are overcome; to provide a lining for the recess which is easily removable and replaceable; to provide a lining which is a unit in itself and which may be manufactured in standard sizes and kept in stock in a weaving mill available for immediate placing in shuttles in which the 55 linings have become useless through wear. The invention further includes all of the other various objects and novel features of construction and arrangement hereinafter more definitely specified and described.

In the drawings, in which like numerals designate like parts in the different figures, Fig. 1 is a plan view of a shuttle of standard type embodying my invention; Fig. 2 is a sectional view on the line 2—2 of Fig. 1; 60 Fig. 3 is a sectional view on the line 3—3 of Fig. 1; Fig. 4 is a sectional view on the line 4—4 of Fig. 2; Fig. 5 is a side elevation partly in section of one form of a lining as used in my invention; Fig. 6 is a sectional view on the line 6—6 of Fig. 5; Fig. 7 is a side elevation of another form of lining; Fig. 8 is a sectional view on the line 8—8 of Fig. 7, and Fig. 9 is a plan view of a form of backing or carrier for the fur or 65 other suitable material before the latter is secured thereto.

The shuttle 1 is of a standard type provided with the usual opening or recess 2 in which the bobbin or tube 3 of rayon 4, or the 80 like, is carried on the usual slotted pivoted holder 5.

In providing a lining within the shuttle of fur or other suitable material for the purposes aforesaid, I use a backing or carrier 85 6 of a material, preferably metallic, such as tin, which is adapted to be easily bent or formed to fit snugly the curvature of the bottom of the recess 2. This backing is preferably first formed into a blank of the desired dimensions and shape by a die. The backing 6 forms a substantially semi-cylindrical shoe having a bottom and side portions and conforming to the configuration of the bottom and sides of the recess in the 90 shuttle. This shoe, which presents a concave face to the flexible fur-like material or fur, supports the same throughout the entire 95 contour thereof.

The blank preferably is provided with 100 narrowed or reduced ends 7, 7 which afford means whereby the lining is securely but removably retained within the shuttle. As shown in Figs. 1, 2, 5 and 7, one or both of the ends 7, 7 may be bent or rolled to form 105 collars through which the pins 8, 8 pass, or, if desired, one or (as shown in Fig. 9) both of the ends may remain flat and extend un-

der said pins 8, 8, the engagement between said ends and said pins operating to hold the lining in position. When it is desired to remove the lining this may be easily done by withdrawing one or both of said pins, it being necessary, of course, in the embodiment shown in Fig. 1 to withdraw both pins.

When a metallic backing is used I preferably attach the fur or other suitable material 10 to the blank while it is flat, using preferably rivets 10 or staples 11 as the means of attachment although it will be understood that adhesives or any other means may be employed as desired; if an adhesive is used 15 the attendant disadvantages under the present practice above mentioned are to a great extent eliminated by reason of the convenience of handling of my device. After the fur-like material has been secured to 20 the blank the latter may be formed manually or otherwise so as to conform to the curvature of the bottom of the recess 2, placed therein, and the pins 8, 8 are then passed through or over the ends 7, 7 as above described to hold the lining in operative position.

In practice I have found that a thin metallic backing such as tin is very satisfactory but it will be understood that a 30 backing of any material adapted to carry the fur or fur-like material and formed to be removably fitted within the recess in the shuttle may be used; it will be further understood that the backing may be initially 35 molded or formed to fit said recess and the fur-like material attached thereto afterward.

While I have herein described embodiments of my invention I do not thereby desire or intend to specifically limit myself to the precise details of construction and arrangement of parts to which I have referred as the same may be modified and varied from the forms shown in the drawings and herein described without departing from the spirit 45 and scope of the invention as defined in the appended claims.

Having thus described my invention, I claim and desire to protect by Letters Patent of the United States:

50 1. A removable lining for the bobbin recess in a weaver's shuttle comprising a fur-like material, a backing therefor, consisting of a relatively stiff shoe having bottom and side portions and supporting the fur-like material substantially throughout the entire contour thereof, means for attaching said material to said backing, and means for retaining said lining within said recess.

60 2. A removable lining for the bobbin recess in a weaver's shuttle comprising a fur-like material, a backing therefor consisting

of a shoe having a curved bottom and sides and supporting the fur-like material substantially throughout the entire contour of the same and conformable to the bottom and sides of said recess and means for retaining said lining within said recess.

65 3. A removable lining for the bobbin recess in a weaver's shuttle adapted to partially surround the threaded bobbin and comprising fur-like material, a backing therefor consisting of a substantially semi-cylindrical shoe conforming to the configuration of the bottom and sides of the bobbin recess in the shuttle and supporting the fur-like material throughout the entire contour of the same and means at the ends of said backing adapted to engage means carried by the shuttle whereby said lining is retained within said recess.

70 4. A removable lining for the bobbin recess in a weaver's shuttle comprising fur-like material, a backing therefor, said backing comprising a curved body portion having a bottom and sides to which said material is secured and which supports the fur-like material throughout the entire contour thereof, said body portion having reduced extended end portions adapted to engage means carried by the shuttle for retaining 75 said lining within said recess.

80 5. In a weaver's shuttle the combination of a threaded bobbin within the opening provided therefor, a removable lining for said opening, said lining comprising fur-like material with which said bobbin contacts, and a metallic backing comprising a main substantially semi-cylindrical portion to which said material is attached and which supports the fur-like material throughout the entire contour thereof, said backing having reduced end members, and pins carried by said shuttle adapted to engage said end members whereby said lining is held within said opening.

85 100 6. In a weaver's shuttle the combination of a threaded bobbin within the opening provided therefor, a removable lining for said opening, said lining comprising fur-like material with which said bobbin contacts, and a backing for said material comprising a substantially semi-cylindrical body portion supporting the fur-like material throughout the entire contour thereof and annular end portions, and removable pins carried by said shuttle adapted to engage the end portions whereby said lining is retained within said opening.

105 110 115 In testimony whereof I have hereunto set my hand this 12th day of January, 1927.

WILLIAM H. HARRISON.
